BRACKET FOR CURTAIN RODS

David H. Rosenberg, New York, N. Y.

Application May 16, 1933. Serial No. 671,369

9 Claims. (Cl. 156—22)

This invention relates generally to brackets for curtain rods and more particularly to a combined bracket and ornamental device.

An object of my invention is to provide a bracket that is adapted to mount a plurality of curtain rods and at the same time is ornamental in appearance.

Another object is to provide such a bracket with means for mounting curtain rods having ends of different constructions.

Another object is to provide such a bracket with means for mounting a plurality of curtain rods in alignment to facilitate hanging a long curtain and a valance.

Still another object is to provide such a bracket with rod mounting means at various positions and levels to accommodate various structures of window frames.

A still further object is to provide such a bracket with means for mounting the curtain rods in stationary and swinging positions.

Another object is to provide a bracket with means for mounting an ornament.

Another object is to provide such a bracket with means for mounting on its support so that the fastening means and the mutilations caused by such fastening means when the bracket is removed are concealed from view.

Other objects and advantages will be apparent from the description of my invention to follow taken in connection with the accompanying drawing in which—

Figure 1 is a front elevation of the top portion of a window frame with my improved bracket mounted thereon.

Figure 2 is a front view of my improved bracket.

Figure 3 is a side view thereof.

Figure 4 is a top plan view.

Figure 5 is a perspective view of a portion of the top of a window frame with my improved bracket mounted thereon at the top of the frame and showing a curtain rod mounted swingingly.

Referring to the drawing in detail, my improved bracket comprises a vertical body portion 10 formed of metal of any suitable kind, a horizontal roof portion 11 formed integrally with the vertical portion and extending to the front and back of said vertical portion. This roof 11 is shown as formed by bending the material upon itself, but it may be formed of a separate piece and secured to the vertical portion in any desired manner. Formed on one side of the body portion 10 is a side wall 12. This wall 12 may have a reduced bottom end 13 for the sake of appearance and for economy if desired. A shelf

14 is formed at the lower edge of the vertical body portion 10 where it intersects with the side wall 12. This shelf is provided with an opening 15.

The roof 11 is provided preferably on one side 60 of the vertical wall with upstanding pins or studs 16 preferably positioned in alignment. Formed in this roof portion 11 preferably on the other side of the vertical wall are a series of aligned openings 17 for the reception of nails 65 or other fastening means. Also formed in the roof 11 preferably adjacent the end thereof adjacent the side wall 12 and adjacent the front edge thereof is a larger opening 18. This opening 18 in the roof and the opening 15 in the 70 shelf 14 are in alignment as shown in Figure 4.

Mounted on the side wall 12 on the interior thereof are spaced pins or studs 19. These studs 19 extend inwardly and upwardly, and may be mounted so that the upstanding portions thereof 75 are in alignment or one stud may extend in further than the other as shown in Figure 2. These studs are mounted on the side wall outwardly of the front edge of the roof 11.

A socket member 20 may be formed integrally 80 on the outside of the wall 12 and preferably is disposed in alignment with the studs 19. An ornamental member 21 such as a spear head may have its shank portion 22 removably mounted in the socket 20. This ornamental member 21 may 85 take any shape desired.

In Figures 2, 3 and 4, I have shown a bracket for use on the right hand side of a window frame. In a bracket for use on the left hand side, the side wall 12 is formed on the left hand end of 90 the body portion 10. Such a bracket is shown in Figure 1 at the left side of the window frame.

In using my improved bracket, curtain rods with angled ends or with straight ends may be used. In Figure 1, I have illustrated my improved bracket mounted on the underside of the upper sill of the window frame 23. This mounting is effected by driving nails or other fastening means upwardly through the openings 17 in the roof portion and into the underside of the 100 sill. When thus mounted the vertical wall 10 conceals the fastening means and any mutilations caused by the fastening means will not be seen when the bracket is removed. In Figure 1 is illustrated an ordinary curtain rod 24 having 105 angled ends with openings therein. Each of the angled ends is mounted on one of the lower studs 19, in this view being shown on the innermost stud 19. These rods are usually adjustable lengthwise. The rod 24 slidably mounts a long 110

curtain 25 by means of rings 26, only a portion of the length of the curtain 25 being shown.

Another rod 27 similar in construction to the rod 24 has its angled ends mounted on the other outer studs 19 so that its elongated body portion is spaced outwardly from the body portion of the rod 24. A valance or fringe 28 is mounted on this rod 27. The ornamental member 21 forming an extension of the rods adds to the pleasing appearance of the window. The rods 24 and 27 could, of course if desired be mounted on the upper studs 16.

It will also be understood that curtain rods having straight ends with openings may be mounted on either studs 16 or 19.

In Figure 5 my improved bracket is shown mounted on the upper surface of the upper rail of the window frame 23. This is effected by placing the inner extension of the roof 11 on the upper surface and driving nails or other fastening means through the openings 17 into the upper sill. When thus mounted the fastening means and any mutilations caused by such fastening means when the bracket is removed are hidden. Only the right hand end of the window frame is shown. In this view a curtain rod 29 having its angled end mounted in the aligned openings 18 and 15 is shown supporting the curtain 25, only a short length of the curtain being shown. The rod 29 with its curtain 25 is adapted to swing toward and away from the window frame as will be understood. A similar rod is of course similarly mounted on a bracket on the other end of the window as will be understood. By reason of this construction, instead of pulling curtains apart for any desired purpose, the curtain is swung outwardly to the extent desired.

Various changes in details might be made without departing from the principle of my invention and I desire therefore to be limited only by the state of the prior art and the appended claims.

I claim:

1. A bracket for mounting a curtain rod comprising a body portion, a roof portion having an opening for the reception of fastening means and means carried by the roof portion for detachably mounting a curtain rod.

2. A bracket for mounting curtain rods comprising a vertical body portion, a horizontal roof portion having openings for the reception of fastening means and a plurality of devices carried by said roof for mounting curtain rods.

3. A bracket for mounting curtain rods comprising a vertical body portion, a horizontal roof portion having openings for the reception of fastening means and a plurality of studs mounted on said roof for detachably mounting curtain rods.

4. A bracket for mounting curtain rods comprising a vertical body portion, a horizontal roof

portion having openings for the reception of fastening means, means on said roof portion for mounting curtain rods, a side wall portion mounted at one end of the body portion and means on said side wall portion for mounting curtain rods.

5. A bracket for mounting curtain rods comprising a vertical body portion, a horizontal roof portion having openings for the reception of fastening means, studs on said roof for mounting curtain rods, a side wall portion mounted at one end of the body portion and studs on said side wall portion for mounting curtain rods.

6. A bracket for mounting curtain rods comprising a vertical body portion, a horizontal roof portion having openings for the reception of fastening means, said roof portion being formed with an opening adjacent one end, and a shelf mounted at one end of the body portion and spaced from the roof portion, said shelf being formed with an opening in alignment with the opening in the roof adjacent its end.

7. A bracket for mounting curtain rods comprising a body portion, a roof portion having openings for the reception of fastening means, a side wall, studs on said side wall for mounting curtain rods and a socket member mounted on said side wall and extending outwardly therefrom for the reception of an ornamental device.

8. A bracket for mounting curtain rods comprising a vertical body portion, a horizontal roof having openings for the reception of fastening means and having an opening adjacent its end, spaced studs on said roof for mounting curtain rods, a side wall formed at one end of said body portion, spaced studs on said side wall for mounting curtain rods, a shelf formed at the lower edge of said body portion and adjacent the wall portion, said shelf being formed with an opening positioned in alignment with the opening in the roof adjacent its end for swingingly mounting a curtain rod.

9. A bracket for mounting curtain rods comprising a vertical body portion, a horizontal roof portion having openings for the reception of fastening means and having an opening adjacent its end, spaced studs on said roof for mounting curtain rods, a side wall formed at one end of said body portion, spaced studs on said side wall for mounting curtain rods, a shelf formed at the lower edge of said body portion and adjacent the wall portion, said shelf being formed with an opening positioned in alignment with the opening in the roof adjacent its end for swingingly mounting a curtain rod and a socket member mounted on said side wall and extending outwardly therefrom for the reception of an ornamental device.

DAVID H. ROSENBERG.
